FRANCIS KINGSLEY, OF PELHAM MANOR, NEW YORK.

METHOD OF POLISHING SHOES.

Application filed April 19, 1922. Serial No. 555,560.

The polishing of shoes by hand as evolved through the ages may be said to consist generally, with variations, of the cleaning of the shoe, the application of the polish, the slow and tedious but uniform "brushing up" with a hand brush and the final finishing off with a soft cloth used possibly in conjunction with an enamel. The steps involved are matters of common knowledge and fair results might be obtained by a tyro. In the present day, however, there is a decided trend towards specialization in shoe shining, as in other trades and the speeding up of the operation by the use of power driven brushes. It has been found in practice that the introduction of a high speed power driven brush changes the conditions by its physical action in such respects as to give rise to the problem of securing eventually a smooth finish on the surface of the shoe. The complete shining operation with a power driven brush is essentially one involving speed and is so represented to the public. The high speed brush with its stiff bristles creates considerable heat in the polish to which it is applied with the result that the volatile constituents are dried out very quickly and the waxy residue hardened very rapidly and unevenly, the impress of the bristles therein leaving the surface very rough. This roughened surface by reason of its irregularity lacks brilliance since the reflected rays of light are broken up. This condition is not bettered appreciably by the use of the usual soft polishing cloth since the hardened wax constituents of the polish maintain their set when such a cloth is passed over them. To provide a shine which has a luster equal to a hand shine (given, of course, at the expense of much greater time,) and one which is satisfactory to the discriminating public, becomes then, the critical problem where a high speed power driven brush is employed. The present invention, has for its principal object to provide a method of polishing shoes with a power driven brush which shall insure a polish of equal brilliance with that secured by the tedious hand brushing and without the loss of an appreciable amount of time. In accordance with the method it is proposed to remove the unsatisfactory rough finish created by the power driven brush by means of a step which involves the use of a cloth whose fibres are of such size and so woven and of such texture as to constitute a sort of "file" which when drawn over the irregular hardened surface left by the brush will remove the tiny irregularities thereon and give to the surface of the shoe a smooth regular finish of brilliance. The action of the cloth thus employed may be accelerated when the method is practised in its most effective form. The fibres of the cloth are prepared by painting them with a solution of wax which hardens and binds the fibres together and itself has a filing action on the smooth similar or waxy composition over which it is drawn. This follows from the fact that similar substances when passed over one another give the most effective abrasive action. The final step of the improved method consists in passing a soft cloth over the surface in order to remove the wax dust and smooth out the fine scratches which the hard rough cloth tends to produce on the surface of the wax film.

For a better understanding of the invention there has been illustrated in the accompanying drawings, in a very diagrammatic and highly exaggerated form a portion of a suitable rough hard cloth and the surface of a shoe after being brushed and before the cloth is applied thereto.

In the drawings:

Figure 1 illustrates in exaggerated form the surface of an abrading cloth which has been painted with wax.

Figure 2 illustrates in cross sectional form a shoe to the surface of which has been applied a polish which has been dried out quickly by a high speed power driven brush.

Figure 3 shows a fragment of suitable cloth showing the relation of the fibres thereof.

In polishing shoes with a power driven brush it is proposed to evaporate very quickly the volatile constituents of the polish after it has been applied to the surface of the shoe, the saving of time in this step over the hand method being one of the important advantages in such a shining operation. The very factor which makes for speed, however, to wit, the great heat generated in the polish, makes for certain disadvantages in that the volatile constituents are driven off so quickly that the waxy residue is left in a hardened and very irregular condition on the surface of the shoe. The waxy particles are not worked down during the progress of the brushing operation to a uniform surface as is the case in a hand operation. The character of the surface left after the use of a

power driven brush is indicated on a greatly enlarged scale at *a* in Figure 2. The tiny irregularities break up the reflected rays of light so that the surface has no brilliance. The problem is to file down these irregularities as quickly as possible by some means which will leave a generally brilliant surface ready for the final polishing cloth. In the improved method of shining it is proposed to employ for this purpose a loosely woven cloth having hard rough fibres which in the preferred form are in such relation as to most effectively do the filing required and exert a greater abrading action than the brush. As indicated in Figure 2, for instance, a suitable cloth will include coarse fibres *b* which extend transversely thereof and smaller fibres *c* which extend longitudinally thereof, these fibres being of very hard texture loosely woven. To accelerate their filing action when the cloth is drawn across the waxy film on the shoe the surface of the cloth is painted with a waxy compound indicated at *d* in Figure 1 which not only binds the fibres of the cloth together as it dries out but also hardens the filing surface. In this connection, advantage is taken of the fact that similar materials when rubbed across one another have the most effective abrading action.

Having in mind the difficulties to be met in the practice of a method which includes as a step the use of a high speed power driven brush, it may be said that the improved method consists generally in applying polish to the shoes by any suitable

means; brushing the polish with a high speed power driven brush which will quickly evaporate the volatile constituents; filing off the hard rough surface left by the brush in its quick action, with a hard loosely woven cloth which will give a greater abrading action to file off the irregularities; and finally finishing off with a soft cloth for the purpose of wiping off the wax dust and smoothing out any little scratches produced on the surface of the wax film by the hard rough cloth.

What I claim is:

1. The herein described method of rapidly polishing shoes which consists in applying polish to a shoe, brushing it with a high speed power driven brush, rubbing the surface with a hard loosely woven cloth having a greater abrading action than said brush, and then removing the powder resulting from the abrading action of said cloth with a smooth soft cloth.

2. The herein described method of rapidly polishing shoes which consists in applying polish to a shoe, brushing it with a high speed power driven brush until the volatile constituents are evaporated, then filing off the hardened waxy irregularities left on the surface with a loosely woven cloth having hard fibres coated with a waxy compound and a greater abrading action than said brush, and removing the waxy filings with a smooth soft cloth.

This specification signed this 18th day of April A. D. 1922.

FRANCIS KINGSLEY.
